ATTORNEY.

UNITED STATES PATENT OFFICE.

KARL HEINEMANN, OF DUSSELDORF, GERMANY, ASSIGNOR TO RHEINISCHE METALL-WAAREN-UND MASCHINENFABRIK, OF DUSSELDORF-DERENDRÖF, GERMANY.

SAFETY DEVICE FOR AUTOMATIC FIREARMS.

Application filed November 15, 1928, Serial No. 319,538, and in Germany August 25, 1926.

In automatic fire arms a spring, the so called closing spring, is tensioned by opening the breech which spring afterwards on extending returns the breech into the closed position in the barrel. If after firing the breech is automatically opened by the force of the powder gases, the closing spring simultaneously serves as a brake for annulling the kinetic energy stored in the running back masses, the breech and eventually the barrel also.

A regular automatic operation of the arm always requires that the closing spring acts with a certain force upon the movable masses against the action of the powder gases. If the force of the spring is considerably reduced by the spring jamming or becoming worn out, or if by rupture of the spring this force ceases altogether, either the automatic action of the arm is stopped or the unbraked running back masses meet with great force the fixed limiting stops of the arm which thereby may be destroyed. The breech is opened thereby too early and the operator will be exposed to danger by powder gases escaping backwards.

These draw-backs are obviated according to the present invention by means of a safety device which automatically prevents the release of the tensioned percussion device for firing purposes, whereby the force applied by the closing spring to the breech is reduced below that necessary and admissible for the regular forward and backward running of the movable masses. The object aimed at is obtained by a safety member influenced by the force of the closing spring in such a manner, that, by the normal pressure of the closing spring, it is brought out of the locking position into a position ready for allowing the release of the percussion device, whereas, after the force of the closing spring has been reduced below a certain degree, the safety member is by the load of a spring automatically brought into the locking position in which the release of the percussion device is prevented.

The safety device may, in a well known manner, simultaneously be used to automatically prevent the release of the percussion device and thereby the firing at not perfectly closed breech, if the safety member is directly or indirectly connected to the closing spring in such a manner, that it is subjected to the force of said spring and brought by

same from the locking position into the position ready for acting only, when the breech is perfectly closed.

The safety device may be used in connection with all kinds of automatic fire arms, i. e. arms having a fixed or a sliding barrel, a locked or unlocked breech and irrespective of particular breech constructions (straight moving, rotatable or toggle joint breeches).

In the accompanying drawing the invention is shown by way of example in connection with an automatic fire arm provided with a toggle joint breech.

Fig. 1 shows the breech of the arm, the side wall of the casing being removed, the percussion device is tensioned and the breech is closed. Fig. 2 is a plan view of Fig. 1 partly in section.

The breech device consists in known manner of the breech portion *a*, the two-part toggle lever *b*¹, *b*², and the closing spring *c*. By pressure exerted by the bearing *c*¹ of the bolt of the closing spring upon a projection *b*³ of the toggle joint part *b*² pivoted upon a pin *b*⁴ carried by the casing of the arm, the toggle joint is brought into the stretched position and thereby the breech portion *a* is brought into the closed position.

The percussion device consists of the spring actuated cock *d* which is held in its tensioned position by the tension member *e*. The trigger *f*, pivoted in the casing of the arm, carries at its upper end the spring actuated pivoted trigger tongue *g* the front end of which is, in the position of rest of the trigger *f*, situated a small distance above the rearwardly extending lever arm *e*¹ of the tension member *e*.

According to the invention a safety lever *h* is pivotally arranged between the closing spring device *c*, *c*¹ and the trigger device *f*, *g* in such a manner, that its arm *h*¹ extends into the path of the movable closing spring bolt *c*¹, while its other arm *h*² is situated above the tongue *g* pivoted to the trigger *f*. A spring *i* acting upon the arm *h*² tends to move the safety lever *h* against the tongue *g* and simultaneously holds the second arm *h*¹ of the safety lever *h* in engagement with the bolt *c*¹ of the closing spring *c*.

When the breech is closed, the bolt *c*¹ of the closing spring *c* is shifted rearwardly so far, that the safety lever *h* is, against the action of the spring *i*, in such a position, that the arm *h*² has no effect upon the trigger *f*.

tongue *g*. If now the trigger *f* is drawn back, the tongue *g* comes to lie upon the arm *e*¹ of the tension member *e* which is pressed down and thereby releases the tensioned cock *d*.

5 If after firing the breech is opened by hand or automatically into the position shown in dash-and-dotted lines in Fig. 2, the projection *b*³ of the toggle lever *b*² presses forward the bolt *c*¹ of the closing spring *c*, whereby 10 the closing spring *c* is compressed or tensioned. Under the pressure of the spring *i* the arm *h*¹ of the safety lever *h* follows the movement of the bolt *c*¹, whereby the second arm *h*² of the safety lever *h* presses upon the 15 trigger tongue *g* which is, against the action of the spring *f*¹, turned about the pivot pin carried by the trigger *f* and moved out of the path of the arm *e*¹ of the tension member *e*. It is now impossible to influence the 20 percussion device by the trigger device. If then the trigger *f* is drawn back, the tongue *g* turns downward behind the arm *e*¹ of the tension member *e* and no release of the tensioned cock *d* occurs.

25 The same effect is obtained if the pressure of the closure spring upon the bolt *c*¹ is, by rupture or becoming worn out of the spring, reduced to such an extent, that the spring *i* overcomes the still remaining force 30 of the closing spring and swings the safety lever *h* in an anti-clockwise direction, whereby at the one hand the bolt *c*¹ of the closing spring is pressed forward and at the other hand the tongue *g* of the trigger *f* is swung 35 backward out of the range of the arm *e*¹ of the tension member *e*. The force of the spring *i* is so chosen, that the lever *h* is automatically swung by the spring *i* into the locking position in which the trigger device has no influence 40 upon the percussion device, as soon as the force of the closing spring *c* is reduced below that necessary and admissible for the regular rearward and forward running of the breech portions.

45 In the example shown, the force of the closing spring *c* is transmitted to the safety member *h* by the movable bolt *c*¹ of the closing spring acting upon the breech portion *a*. According to another construction this may be 50 effected directly by the breech portion *a*, or the closing spring may be caused to act upon the safety lever *h* by way of the second bearing *c*² of the closing spring which in this case would then also be made movable. In this 55 case a safety device is obtained which becomes effective only if the closing spring weakens or breaks which, however, allows firing even if the breech is not perfectly closed.

Instead of preventing the release of the 60 percussion device by preventing the trigger device from influencing the percussion device, as described above, the safety lever could be caused to directly lock the trigger—or percussion device in the manner of the locking

members of the ordinary hand actuated safety devices. Of course, the safety lever must then be of other construction, for instance, be formed and arranged as a slide. Obviously, the fire arm may have, besides the safety device according to the invention, also a hand actuated safety device in which case, for the purpose of simplifying and reducing the single parts, both devices are preferably organically connected to each other. To obtain this, a locking member for the trigger device or the percussion device may, for instance, be controlled automatically by the force of the closing spring as well as by hand by means of a suitable handle.

What I claim is:

1. In a safety device for automatic fire arms, a breech, a closing spring for said breech, a percussion device, a safety device cooperating with said percussion device and a second spring adapted to influence said safety device, said safety device being, under the influence of said closing spring, brought out of the locking position into a position ready for releasing the said percussion device when said closing spring has its normal pressure, but being, under the influence of said second mentioned spring, brought automatically into a locking position preventing the release of said percussion device as soon as the force of said closing spring is reduced below that necessary and admissible for the normal rearward and forward running of the movable masses.

2. In a safety device for automatic fire arms, a breech, a closing spring for said breech, a bolt movably arranged in said closing spring, a bearing provided at said bolt, a percussion device, a safety device cooperating with said percussion device and a second spring adapted to influence said safety device, said closing spring influencing said safety device by said bearing acting upon said breech if said breech is perfectly closed only, so that firing is prevented not only if said closing spring is out of order but also, in known manner, if the breech is not perfectly closed.

3. In a safety device for automatic fire arms, a breech, a closing spring for said breech, a bolt movably arranged in said closing spring, a bearing provided at said bolt, a percussion device, a safety device cooperating with said percussion device and a second spring adapted to influence said safety device, said closing spring influencing said safety device by said breech if said breech is perfectly closed only, so that firing is prevented not only if said closing spring is out of order but also, in known manner, if the breech is not perfectly closed.

In testimony whereof I have affixed my signature.

KARL HEINEMANN.
